(57) **CLAIM**

An ornamental design for a modular illumination and aiming apparatus, as shown and described.

DESCRIPTION

FIG. 1 is a front perspective of a modular illumination and aiming apparatus, in accordance with the present invention; FIG. 2 is a top perspective of a modular illumination and aiming apparatus, in accordance with the present invention; FIG. 3 is a bottom perspective of a modular illumination and aiming apparatus, in accordance with the present invention; FIG. 4 is a first side perspective of a modular illumination and aiming apparatus, in accordance with the present invention;

FIG. 5 is a second side perspective of a modular illumination and aiming apparatus, in accordance with the present invention;

FIG. 6 is a front end-side perspective of a modular illumination and aiming apparatus, in accordance with the present invention; and,

FIG. 7 is a back end-side perspective of a modular illumination and aiming apparatus, in accordance with the present invention.

The broken line(s) in the drawings disclose the unclaimed portions of the modular illumination and aiming apparatus only and form no part of the claimed design.

1 Claim, 6 Drawing Sheets

Related U.S. Application Data

division of application No. 15/142,597, filed on Apr. 29, 2016, now Pat. No. 10,386,160.
